BUS SEAT SECURING MEANS

Robert S. Turner, Oklahoma City, Okla.

Application August 5, 1941, Serial No. 405,550

6 Claims. (Cl. 45—137)

This invention relates generally to the class of chairs and seats and pertains particularly to improvements in means for securing chairs or seats to the floor or other support.

The present invention is directed primarily to an improved means of securing in place seats used in buses, train coaches or the like.

In the cleaning of buses and train coaches or other structures used by the public and where a number of chairs or seats must be provided which are secured in position, it is very difficult, particularly in buses, to thoroughly clean the same without removing the seats. At the present time bus seats and the seats or chairs used in train coaches, airplanes and other vehicles are secured to the floor by the use of bolts, and when it is necessary to remove and replace such seats, considerable time and labor are involved; and it is also necessary to employ the services of at least two men to do the job.

The principal object of the present invention, in view of the foregoing, is to provide an improved method or means of securing bus, train coach, airplane or like seats, to the supporting floor structure in such a way that the connection between the seat and the floor structure may be easily and quickly broken and established as necessary so that such seat may be removed from position or replaced with a minimum of effort and very quickly.

Another object of the invention is to provide in seats of the character stated, an improved leg structure which not only provides an attractive support for the seat but provides a housing for the seat securing mechanism.

Still another object of the invention is to provide means for securing the seat legs to a floor or other support which may be secured or released without the use of special tools, and which is of strong and durable construction, and when in secured position cannot work loose to accidentally release the seat.

The invention will be best understood from a consideration of the following detailed description taken in connection with the accompanying drawing, it being understood, however, that the invention is not to be considered as limited by the specific illustration or description but that such illustration and description constitutes a preferred embodiment of the invention.

In the drawing:

Fig. 1 is a view in front elevation of a seat constructed in accordance with the present invention.

Fig. 2 is a sectional view taken substantially on the line 2—2 of Fig. 1.

Fig. 3 is a view in transverse section taken substantially upon the line 3—3 of Fig. 2.

Fig. 4 is a sectional view in a vertical plane taken at right angles to the axis of oscillation for the floor attached hook, showing the latter disconnected from the keeper hook.

Fig. 5 is a view in bottom plan upon a reduced scale, of one leg of the structure.

Fig. 6 is a view in elevation of the bolt securing tongue which is attached to a side leg.

Referring now more particularly to the drawing, the numeral 1 generally designates a seat which is conventionally illustrated and which is of the general construction commonly used in buses, train coaches and like public conveyances, such seats having a bottom frame, to which the supporting legs are attached and which is indicated by the numeral 2.

In accordance with the present invention, the frame 2 has secured to the transverse bars 3 which form a part of its construction, the legs, which are indicated generally by the numeral 4, and which are of hollow form so as to provide a housing for the hereinafter described securing mechanism. These legs may be shaped from suitable sheet metal and they have the upwardly converging side walls 5 which are joined at their forward edges by the rounded front wall 6, while at their rear edges they are angled to extend downwardly and rearwardly and are joined by the integral rounded back wall 7 which has a downwardly and rearwardly extending slope. The upper edges of the four walls of the hollow legs are suitably secured as by welding or in any other suitable manner to the frame bar 3, while the bottom of the leg structure is closed by the bottom wall 8. Thus it will be seen that the legs are of streamlined form and because of the rearwardly sloping back walls which extend beyond the point of connection between the top of the leg at the rear thereof and the frame, will function to hold the seats firmly and prevent any tendency to rearward tipping.

A portion of the floor structure is indicated by the numeral 9 and in accordance with the present invention there are secured to the floor two holding units each of which is indicated generally by the numeral 10, each of these units being located so that it may extend upwardly through the opening 11 in the bottom wall 8 of a leg.

Each of the units 10 comprises an eye-bolt having a shank portion 12 which extends through the

floor and receives upon the threaded lower end thereof the lock nut 13, while the upper end or eye of the bolt which is indicated by the numeral 14, lies above the plane of the top of the floor.

Overlying the upper end of the eye-bolt is a box or housing 15 which is secured to the floor 9 by screws 16 or in any other suitable manner. The box extends upwardly into the hollow leg through the opening 11 thereof and the top wall is provided with an opening 17 as shown in Fig. 2.

The eye 14 of the eye-bolt has extended therethrough a pivot pin 18 which pivotally secures to the eye-bolt the two downwardly convergent legs 19 of a yoke which is indicated generally by the numeral 20. This yoke as shown in Figs. 2 and 3 is relatively long and two legs extend upwardly into the substantially semi-circular portions 21 which are joined together by the transverse loop or bar 22 so that the yoke also forms a hook-like structure.

As will be readily understood the securing yoke 20 swings on the pivot 18 lengthwise of the leg or transversely of the seat from the front to the rear thereof. Within the box 15 there is located at the back of the yoke a rubber bumper 23 and on the opposite side of the yoke from this bumper is a similar body 24 having a top flange portion 25 which extends across the opening 17 and constantly urges the yoke to swing rearwardly against the block 23.

The side walls 5 of each leg have secured therein directly opposite or transversely aligned positions, the pair of guide collars 26, shown particularly in Fig. 3 and extending through these collars is a bolt 27 which lies directly above and parallel with the pivot 18 of the underlying unit. This bolt 27 at one end has the head 28 while the opposite end has threaded thereon nut 29.

At substantially midway between its ends the bolt 27 carries a collar 30 which is formed integrally with a hook finger 31, the point of which describes a circle around the bolt when the latter is turned or rotated. The height of the bolt 27 above the adjacent pivot 18 is such that, when the hook 31 is turned down as in Fig. 4 the looped portion of the yoke can be swung in to receive the bolt 27 and the yoke will straddle the hook 31. The location of the bar portion 22 of the yoke, when the latter is in disconnected position is such that when the hook-finger 31 is turned upwardly its point will pass through the yoke and around and over the bar 22 so as to establish a connection between the hook and the yoke and at the same time the yoke will be swung forwardly so that the bolt 27 will enter the looped portion of the yoke as shown in Fig. 2. In this manner the yoke will be securely connected with the bolt 27 which lies adjacent thereto and also the resilient flange 25 will be under compression so that when the bolt 27 is reversely turned so as to release the hook-finger from the yoke bar, the yoke will be forced to the rear, to the position in which it is shown in Fig. 4 thus completely disconnecting the leg from the floor. As will be readily appreciated the leg may then be lifted directly off the adjacent unit 10.

In order to facilitate positioning the leg properly on the floor so that the units 10 may enter the openings 11, without difficulty, the bottom 8 of each leg is provided adjacent to its forward and rear ends with a centering pin 32 which is adapted to engage in an opening 33 formed in the floor.

From the foregoing it will be readily seen that

the structure herein described provides a simple but strong and durable and reliable means of fastening to an underlying supporting surface such as the floor or the like, seats of cars, buses, airplanes or other vehicles or structures wherein it is desirable, from time to time, to remove the seats to facilitate cleaning the structure.

While there is a certain degree of tension or strain applied to each yoke when the same is coupled with the overlying keeper finger or hook as shown in Fig. 2, which would tend to prevent accidental disengagement of the part, nevertheless there is provided a locking or securing means in association with each bolt 27 which comprises a resilient metallic strap 34 which is pivotally secured at one end to the adjacent wall 5 by a rivet 35 or any other suitable means and which at its other end is provided with a flanged opening of polygonal contour corresponding to the contour of the head 28 of the bolt. This apertured end of the strap 34 is engaged over the adjacent bolt-head 28 by springing the strap outwardly away from the supporting wall and then turning the strap until it is in the proper position where the opening will receive the bolt-head when the strap is released to move back against the wall.

What is claimed is:

1. In a chair or seat structure, a seat body, supporting legs for the body each comprising a hollow housing having a lower portion adapted to rest upon a supporting structure such as a floor, a rotatably supported hook-shaped finger mounted within each housing, means accessible from outside the housing for rotating the finger, and an element for each housing adapted to be pivotally connected with the leg supporting structure to extend into the housing to a position adjacent the finger, said element being formed at its free end to receive said finger when the finger is rotated in one direction to establish a locking connection with the finger.
2. In a chair or seat structure, a seat body, supporting legs for the seat each comprising a hollow housing having a bottom portion designed to be positioned upon a supporting structure such as a floor or the like, a pair of upstanding floor attached pivoted elements each arranged to extend into a housing and each including a yoke portion, a hook-shaped finger-member within each housing pivotally supported for rotation on an axis extending across the housing to turn the finger through an arc passing through the adjacent yoke, means for turning the finger from outside the housing, means facilitating locating said finger and yoke in operative relation and means engaging each yoke and resiliently urging the same to move away from the pivotal axis of the adjacent finger.
3. In a structure of the character set forth, a body supporting leg, an elongated member horizontally supported for rotation on the leg, a hook-like finger carried by the elongated horizontal member, an elongated upwardly extending yoke member disposed with its lower end beneath the horizontally supported member, means pivotally coupling the lower end of the yoke member to an underlying support upon which the leg rests, means yieldably urging the yoke to a position in which its upper end will be away from the rotatable member, and means maintaining said yoke in a position relative to the elongated member in which said hook-finger will engage therein upon rotation of the elongated member.

gated member and the hook-finger in one direction.

4. In a seat structure, a seat body, a hollow leg for the seat body having a pair of side walls, a bolt extending across the hollow leg and rotatably supported at the ends in said walls, means for rotating the bolt from outside of the leg, a hook carried by said bolt in a position to have its free end moved through a circular path upon turning of the bolt, an elongated member having an open end, means for pivotally coupling said member at its other end with a fixed support upon which the seat leg rests, the hollow leg being manipulated so that the pivotal coupling for the elongated member lies directly below said bolt, means facilitating positioning the leg in a desired position on said support relative to said coupling, and resilient means maintaining said elongated member in a position extending upwardly from the pivoted end thereof across said bolt whereby the open end of the member may be engaged by said hook upon rotation of the same in one direction.

5. A structure as set forth in claim 4, in which said elongated member is laterally bowed at the open end to receive said bolt when the hook engages in said open end, said hook functioning to swing the bowed end of the elongated member toward and into partially encircling relation with the bolt.

6. A securing means for a vertical body sup-

porting leg, comprising a rotatably supported horizontal bolt carried by the leg, means facilitating the rotation of the bolt, a hook-shaped finger carried by the bolt for turning about the axis thereof, an anchor member adapted to be secured to the support for the leg beneath said bolt, an elongated coupling member pivotally attached to said anchor member to oscillate thereon on an axis paralleling the bolt, said coupling member normally extending upwardly beyond the bolt and being formed at its upper end in the shape of an eye to receive said finger, said finger when rotated by the bolt, when the bolt is located directly over the anchor member, by the manipulation of the leg member, being adapted to enter the said upper end of the coupling member and oscillate the coupling member at its upper end toward the bolt to establish a firm connection through the coupling member between the bolt and said anchor member, and a pair of resilient members secured upon opposite sides of the pivoted lower end of the coupling member and functioning to hold the coupling member up but at an inclination from the vertical when the finger is disconnected therefrom, the finger upon engagement with the upper portion of the coupling member during turning of the bolt, effecting oscillation of the coupling member to vertical position against the resistance of one resilient member.

ROBERT S. TURNER.
